UNITED STATES PATENT OFFICE.

HORATIO S. LYNESS, OF LYNN, MASSACHUSETTS, ASSIGNOR TO UNITED SHOE MACHINE CORPORATION, OF PATERSON, NEW JERSEY, A CORPORATION OF NEW JERSEY.

MACHINE FOR TREATING VAMPS.

Application filed October 27, 1922. Serial No. 597,382.

To all whom it may concern:

Be it known that I, HORATIO S. LYNESS, a citizen of the United States, residing in Lynn, in the county of Essex and State of Massachusetts, have invented certain Improvements in Machines for Treating Vamps, of which the following description, in connection with the accompanying drawings, is a specification, like reference characters on the drawings indicating like parts in the several figures.

This invention relates to machines for operating on sheet material and is herein shown as embodied in a machine for perforating and marking vamps for shoes.

In the preparation of uppers for boots, and shoes it is customary to mark certain parts, such as vamps and wing tips, with location marks which subsequently facilitate the presentation of said parts to a machine for performing another operation, for example, a perforating machine which applies either a row of ornamental punchings or a cluster of ornamental punchings in the form of a medallion. Said location marks, or some of them, also serve to indicate the points of attachment of other parts such as the uppers which are subsequently united by stitching to the vamps. The marks are applied in various ways, by hand or by machine, but the operation, heretofore, has been distinct from the ornamenting operation so that for both operations, two presentations of the work have been necessary.

It is an object of this invention to provide an improved machine for applying location marks to vamps or other similar blanks capable of being handled in a similar manner and for ornamenting or otherwise operating upon them in one operation. In the illustrated embodiment of the invention, there is incorporated with a throat gage which locates vamps with respect to a punching machine, a pivoted marker which is moved against the centers of the throats of the vamps to indicate the points of attachment of the uppers. As shown, the marker is actuated yieldingly by a treadle which controls the clutch of a perforating machine.

Another feature of the invention relates to improvements in a throat gage by which blanks such as vamps are located or centered. Heretofore sets of pivoted gage arms

with rolls at the ends have been mounted 55 adjustably on a work support to engage the interior edges of the throats of vamps to center the latter. The substantially point contact of these rolls with the thin material is apt to upset or curl the edges with a 60 consequent lack of that precise positioning which is required for properly locating the perforations. In the illustrated improvement, two long bars arranged to lie in engagement with the interior edges of the 65 vamps along their whole length, are pivotally connected to the sets of gage arms and this long contact avoids upsetting the material.

In referring to the work, the term 70 "vamp" has been repeatedly used throughout the specification and claims. This has been done for the sake of convenience and brevity and not in a limiting manner, it being intended to cover not only vamps in 75 a literal sense but wing tips and other blanks capable of being handled in a similar manner.

These and other features and advantages 80 of the invention will appear from a consideration of the following specification and accompanying drawings in which—

Fig. 1 is a perspective view of the machine;

Fig. 2 is a detail view of a portion of 85 the throat gage and the marker;

Fig. 3 is a perspective view of the throat gage;

Fig. 4 is a vertical central section of the 90 machine;

Fig. 5 is a plan view of a portion of the machine showing a vamp in punching and marking positions;

Fig. 6 is a plan view of a modified form 95 of the invention;

Fig. 7 is a perspective view of the parts shown in Fig. 6; and

Fig. 8 is a vertical central section.

In the machine selected for illustration, the vamps to be treated are inserted between a punch and a punch block and located with respect thereto by a throat gage which is adjustable to take care of different sizes and styles of work. The frame 10 has a detachable punch block or backing surface 100 12 arranged to receive the impact of the punches on a gang punch or die 14 which is removably secured in dovetail ways on

a block 16. The block is formed on the end of a plunger 18 slidable in guides on the frame and reciprocated by toggle arms 20 actuated from the drive shaft of the machine. Any suitable one-revolution clutch, indicated generally at 22 and controlled by a spring-depressed rod 24 connected to treadle 26, may be used.

A vamp support 30 in the form of a flat plate projects from the punch block 12 and is preferably integral therewith. It has a circular opening 32 from which there extends toward the punch a long slot 34. Slidable on the vamp support 30 is a block 36 having a tongue guided in the slot 34 and adjustably held therein by an integral stud projecting down through the slot and threaded for the reception of a clamp nut 38. From the sides of the block 36 there project indicators 40 for cooperation with scored lines of reference 41 on the vamp support. These lines, for instance, may indicate sizes and the slide block 36 can be clamped in any desired position along the slot 34 as determined by the size. To front and rear sets of pivot pins 42 and 44 projecting upwardly from the block 36, there are pivoted front and rear sets of arms 46 and 48 confined between the block and a cover plate 50. The arms are normally pressed toward each other and toward the center of the gage by leaf springs 52 fixed to the block 36. Each set of arms is independently movable against the tension of the springs by cone pointed screws 54 or 56, the conical surfaces engaging the sides of the arms near their pivoted ends.

To furnish a contact of great extent along the inner edges of the vamp throats thus to avoid upsetting the thin material, the front arm on each side of the gage is connected with the rear arm on the same side by a bar 58. The rear end of each bar has a hook 60 extending around a roll 62 on the end of the corresponding rear arm. The hooked connection provides the necessary lost motion between the bar and the arm as the gage is opened and closed to fit the different sizes of vamps.

Hitherto vamps have been provided with location marks to facilitate their presentation to a punching machine and also to indicate the points of attachment of other parts, the marking and perforating being carried out in two distinct operations. One such mark is frequently applied to the center of the vamp at the throat to indicate the point of attachment of the upper. By this invention this mark is applied during the perforating operation. Fixed to the slide block 36 is a block 64 to one end of which there is pivoted at 66 a lever 68, the forward end of which has a downwardly projecting marker in the form of a stab point 70. This point normally overlies the

vamp when in marking position and the distance that the mark is to lie from the edge of the material can be regulated by an adjusting screw 74 threaded in the slide block 36 and passing through a slot 72 in the block 64. The marker is held above the surface of the vamp support by its rear arm 76 from which there projects a headed screw 78 extending into a recess of the block 64 and having a spring interposed between its headed portion and the bottom of the recess. The marker is actuated by a downward extension 82 connected by a spring 84 and a flexible member 86 to the treadle 26. In operation, the vamp to be treated is inserted between the punch block and the punch and around the throat gage which is first adjusted to fit the particular size and style. Upon depression of the treadle, the marker 70 is pressed against the central portion of the vamp near the edge of the throat; thereafter the spring 84 gives and continued depression of the treadle actuates the clutch 22 and starts the machine.

In Figs. 6, 7 and 8 there is shown a modified form of marker which is automatically operated when a punch block is reciprocated towards a piece of work lying on the stripper plate of a fixed die. At 88 is a gang punch or die which cooperates with a reciprocating punch block 90, there being a spring pressed plate 92 interposed between these members to strip the work from the punches. A vamp supporting plate 54, preferably integral with the stripper plate 92, is slit as indicated at 96 to form a spring tongue 98 which yieldably supports a throat gage and marker. A slide plate 100 is adjustably mounted on the tongue 98 and carries a pair of gage arms 102 which may be opened and closed in any desired manner to fit the throats of vamps. This particular gage is similar to that disclosed in Patent No. 1,448,751, granted March 20, 1923 to George Knight, Serial No. 472,709, filed May 26, 1921, to which reference may be had for the details of construction not material to this invention. There is a notch 104 at the center of the vamp support and projecting into this notch is a stab point or marker 106 carried on a spring arm 108 adjustably connected to the slide plate 100 by a screw 110 passing through a slot in the arm and threaded in the plate. In this form of the invention the mark is automatically applied when the work lying on the vamp support is depressed by the punch block against the marker. The tongue 98 and the associated parts are depressed into a recess of the die by the punch block but the forward end of the spring arm 108 strikes the die and supports the stab point 106 for the marking operation.

Although the invention has been shown and described by reference to a specific ma-

chine it should be understood that, in its broader aspects, the invention is not necessarily limited to the particular machine selected for illustration.

5 Having fully described my invention, what I claim as new and desire to secure by Letters Patent of the United States is:

1. In a machine of the class described, mechanism for ornamenting a vamp, means 10 for locating the vamp to receive the ornamentation in the desired locality, and mechanism for indicating on the vamp in a predetermined relation to said ornamentation the point of attachment of an upper when 15 the vamp is positioned for the ornamenting operation.

2. In a machine of the class described, a punch, a punch block, mechanism for relatively moving the punch and punch block 20 to ornament a vamp by a series of perforations, and mechanism for indicating the center of the throat of the vamp as an incident of the perforating operation.

3. In a machine of the class described, a 25 gang punch, a punch block, mechanism for relatively moving the punch and punch block to ornament a vamp, mechanism for marking on the vamp the point of attachment of an upper, and a single throat gage 30 for locating the vamp for both marking and ornamenting.

4. In a machine of the class described, a punch, a punch block, mechanism for relatively moving the punch and punch block to 35 ornament a vamp, means for controlling said mechanism, a vamp marker, and mechanism actuated by said controlling means for operating said marker.

5. In a machine of the class described, a 40 punch, a punch block, mechanism for relatively moving the punch and punch block to ornament vamps, a throat gage for locating vamps of different sizes to receive the ornamentation in the desired localities, and a 45 marker carried by said gage to indicate the centers of the throats of the vamps.

6. In a machine of the class described, a punch, a punch block, mechanism for relatively moving the punch and punch block 50 to perforate vamps, adjustable gage arms to enter the throats of the vamps, means for moving said arms toward or from the punch to locate the perforations on different vamps at the desired distances from the throat, 55 and means adjustable with the arms for marking the points of attachment of other parts to the vamps.

7. In a machine of the class described, a 60 punch, a punch block, mechanism for relatively moving the punch and punch block to perforate vamps, a plate movable toward or from the punch, vamp centering means carried by the plate, and a marker to indicate the points of attachment of other parts to the vamp, said marker being carried by and

movable with the plate as the latter is moved toward or from the punch for locating different vamps.

8. In a machine of the class described, a punch, a punch block, mechanism for relatively moving the punch and punch block to perforate a vamp, means for locating the vamp to receive the perforations in the desired locality, an arm pivoted to said means and having a marker to engage the vamp, 75 and means for moving said arm.

9. In a machine of the class described, a punch, a punch block, mechanism for relatively moving the punch and punch block to perforate a vamp, means for locating the 80 vamp to receive the perforations in the desired locality, an arm pivoted to said means and having a marker to engage the vamp, a lever, and a yielding connection from the 85 lever to the arm to operate said marker.

10. A machine for marking and otherwise operating on vamps, comprising mechanism for treating a vamp, means for locating the vamp to receive the treatment in the desired locality, and mechanism for marking the vamp to indicate the point of attachment of an upper while the vamp is positioned by said locating means.

11. In a machine of the class described, a 90 vamp support, a gage associated therewith arranged to enter the throat of a vamp, and a marker connected to said gage and movable to indicate a desired point of reference on the vamp.

12. In a machine of the class described, a 95 vamp support, a throat gage associated therewith having symmetrically arranged arms adjustable to fit the throat of a vamp, a marker pivoted to the central portion of the gage, and means for moving the marker to indicate on the vamp the point of attachment of an upper.

13. In a machine of the class described, a 100 vamp support, a throat gage adjustably mounted on said support and comprising two sets of pivotally mounted arms symmetrically arranged with respect to a center line, and a bar loosely connecting the set of arms at each side of the center line and arranged to engage the side edges of a vamp 115 throat.

14. In a machine of the class described, a 120 vamp support, a plate adjustably mounted on said vamp support, a pair of front gage arms pivotally connected to said plate, a pair of rear gage arms pivotally connected to said plate, and a bar connecting the end of each front arm with the corresponding rear arm and arranged to engage the side edge of a 125 vamp throat.

15. In a machine of the class described, a 130 vamp support, a plate adjustably mounted on said vamp support, a pair of front gage arms pivotally connected to said plate, and means cooperating with said gage arms to

assist in locating a vamp, a bar pivoted to each front arm and having a hook slidably engaging said cooperating means.

16. In a machine of the class described, a vamp support, a plate adjustably mounted on said vamp support, a pair of front gage arms pivotally connected to said plate, co-

operating rear gage arms, rolls on the ends of one pair of arms, and a pair of bars hooked around the rolls and pivotally connected to the other pair of arms. 10

In testimony whereof I have signed my name to this specification.

HORATIO S. LYNESS.
